UNITED STATES PATENT OFFICE.

ELMER LEE HARMON, OF PITTSBURGH, PENNSYLVANIA.

MOUNTING APPARATUS.

1,146,792.

Specification of Letters Patent. Patented July 20, 1915.

Application filed April 27, 1915. Serial No. 24,326.

To all whom it may concern:

Be it known that I, ELMER LEE HARMON, a citizen of the United States, residing at Pittsburgh, in the county of Allegheny and State of Pennsylvania, have invented certain new and useful Improvements in Mounting Apparatus, of which the following is a specification.

This invention relates to mounting apparatus particularly adapted for use in connection with the mounting of posters, maps, prints, and other purposes wherein it is found applicable, but designed primarily for use in connection with the mounting of posters or maps upon a flexible body, preferably cloth, and has for its object to provide, in a manner as hereinafter set forth, a mounting apparatus for the purposes referred to whereby there is effected a great saving in the flexible body, when mounting a poster or map in accordance with this invention over the method now in general vogue.

A further object of the invention is to provide a mounting apparatus, for the purposes set forth, with means in a manner as hereinafter referred to whereby a uniform stretching of the flexible body for the poster or map is had during the operation of mounting.

30 A further object of the invention is to provide a mounting apparatus for the purpose set forth and in a manner as hereinafter referred to whereby there is effected economy and saving when drying the mounted posters or maps.

35 A further object of the invention is to provide a mounting apparatus for the purpose set forth and in a manner as herein-after referred to whereby a great saving of labor is had, when mounting a poster or map in accordance with this invention over the method now in general vogue.

40 A further object of the invention is to provide a mounting apparatus for the purpose set forth, in a manner as hereinafter referred to, whereby a modified uniform stretching of the flexible body is had during the mounting operation.

45 A further object of the invention is to provide a mounting apparatus for the purpose set forth and in a manner as hereinafter referred to whereby, during the mounting operation there is effected a saving of cloth due to the fact that one is able to mount

posters or maps continuously without loss of cloth, this latter objection being necessary when using the method now in general vogue.

55 A further object of the invention is to provide a mounting apparatus for the purpose set forth, in a manner as hereinafter referred to, with means to provide a solid backing during the mounting of a poster or map and such backing being easily disengaged from the poster or map when mounted and at the same time providing a backing overcoming the necessity of employing grooves in which are mounted posters as in the method now in general vogue.

60 A further object of the invention is to provide a mounting apparatus for the purpose set forth, in a manner as hereinafter referred to, with means to overcome a possibility of the flexible body tearing off its support during the drying process, that is to say after the poster or map has been pasted 65 on the flexible body.

70 A further object of the invention is to provide a mounting apparatus for the purpose set forth, in a manner as hereinafter referred to, with means to automatically 75 drawing the flexible body taut prior to the pasting on the body of the map or poster.

80 Further objects of the invention are to provide a mounting apparatus for the purpose set forth which is comparatively simple 85 in its construction and arrangement, allowing of the continuous mounting of posters or maps, strong, durable, conveniently manipulated, readily set up and comparatively inexpensive.

85 With the foregoing and other objects in view the invention consists of the novel construction, combination and arrangement of parts, as hereinafter more specifically described and illustrated in the accompanying drawings, wherein is shown an embodiment 95 of the invention, but it is to be understood that changes, variations and modifications can be resorted to which come within the scope of the claims hereunto appended.

95 In the drawings wherein like reference characters denote corresponding parts throughout the several views: Figure 1 is a top plan view of a mounting apparatus in accordance with this invention. Fig. 2 is an elevation, broken away, of the apparatus. Fig. 3 is a side elevation of a shiftable back-

ing element. Fig. 4 is an elevation of the apparatus showing the arrangement of the backing element in connection therewith. Fig. 5 is a detail of a sectional elevation. Fig. 6 is a detail in elevation.

The mounting apparatus in accordance with this invention includes one or more track ways, as illustrated in Fig. 1 four track ways, but these latter are merely shown by way of example, and associated with one or more track ways are two backing elements. If but one track way is employed two backing elements are used and these elements are shiftable transversely with respect to the track ways. Each track way consists of an upper continuous rail 1 and a lower rail 2 which has a portion thereof removed, as at 3, for the purpose to be hereinafter referred to. The track rails 1, 2, are formed from channel-shaped members 4, as illustrated in Fig. 5, but the channel-shaped members 4 which form a track rail 1 are reversely disposed with respect to the channel-shaped member 4 which provides the track rail 2. The track rail 1 is supported preferably from the ceiling by inverted yoke-shaped hangers or brackets 6 and the track rail 2 is mounted upon spaced blocks 7 and said track rail 2 is connected with said blocks 7 by yoke-shaped retaining members 8. The track rail 2 has portions thereof disposed downwardly at an inclination as at 9 for a purpose to be presently referred to and each inclined part is arranged to terminate at the slotted portion of the track 2. Traveling in the track rail 1 are series of axles 10 provided with wheels 11 and depending from each of said axles is a hanger arm 12, terminating in a bifurcated member 13. Traveling in the track rail 2 is an axle 14, carrying wheels 15, and projecting upwardly from each of the axles 14 is an arm 16, having a right angular end 17, through which extends a cylindrical rod 18, the latter having a head 19 at its lower end and surrounding the rod 18 and interposed between the head 19 and the angular end 17 is a coil spring 20. The rod 18 extends up through the angular end 17 and has formed integral therewith, as well as offset with respect thereto, a bifurcated member 21. When mounting posters or maps preferably a flexible body is employed and upon which the poster or map is pasted and the said flexible body preferably consists of suitable fabric and which adds to the durability of the poster or map, in fact it increases the life of the map or poster as is obvious. Ordinarily the flexible body is mounted upon a frame and stretched and after which the poster or map is pasted upon the body and then allowed to dry. In some instances the flexible body contracts to such an extent as to split the poster and oftentimes the body is split. In a mounting apparatus in ac-

cordance with this invention it includes a carrier on which the flexible body is detachably connected to the carrier and is capable of being shifted upon the track way to the desired point and during shifting with the flexible body thereon the carrier will be automatically widened to take up any slack in the flexible body.

The carrier consists of flexible sides and a pair of rigid ends. As each of the flexible sides is of the same construction, but one will be described as the description of one will apply to both. Each of the flexible sides consists of a longitudinally extending flexible member 22 which may be constructed of any suitable material, but preferably a strip of fabric is employed, and the member 22 of the top side of the carrier is mounted in the bifurcated member 13 and the flexible member 22 of the bottom side of the carrier is mounted in the bifurcated member 21. One arm of each of the said bifurcated members is of less length than the other, and said arm of less length is one arm of said member. Mounted against the flexible member 22 and arranged in spaced relation are blocks 23 constructed preferably of wood, and said blocks 23 are positioned against the outer face of the flexible member 22 and against the free edge of the short arms of the bifurcated members 13 and 21. The blocks 23 are secured to the bifurcated members 13, 21, by hold fast devices 24 and each of said blocks has projecting therefrom a series of coupling members 25 for the purpose of detachably connecting the flexible backing 26 to the carrier.

Each of the rigid end members is of the same construction and the description of one will apply to the other and each of said end members consists of an upright 26^a, preferably constructed of a strip of wood, and which is loosely connected at its lower end as at 25^a to the bottom side rail of the carrier, the connection being such that the bottom side rail can shift downward and upward when occasion so requires, for the purpose of widening or narrowing the width of the carrier to provide for drawing the flexible member taut, or to permit of the contracting of the flexible body 26. Each of the end members 26^a is connected to the top side rail of the carrier as at 27. As the bifurcated members 13 are secured by the hold fast devices 24 to the flexible member 22 of the top rail of the carrier it is obvious that the carrier is coupled to the hangers-on 12. As the bifurcated members 22 are connected by the hold fast devices 24 to the flexible member 22 of the bottom rail of the carrier it is obvious that the carrier is coupled with the arm 16. The rod 18, spring 20, and angular end 17 of the arm 16, permit of the width of the carrier being increased or diminished when desired and also allow for 130

the contraction of the flexible body when occasion so requires.

- Each of the backing elements consists of a platform 28, carried by a truck 29, carried 5 upon a track 30 disposed at right-angles with respect to a track way and the said trucks 29 are arranged in the space between the cut-out portions of the track rail 2. Carried by the truck 29 is a channel-shaped 10 member 30^a, which when the backing element is in position forms a continuation of a track rail 2 so that the carrier can be shifted without interruption. Secured to the platform 28 is a vertically disposed backing 15 board 31, which is braced as at 32, 33, and said backing board, when in use, is positioned at the rear of a flexible body 26, so that it provides a support for the body 26 when a poster or map is pasted and secured 20 to the flexible body 26. Carried by the backing element in supports 34 is a vertically disposed roller 35, and which, when the backing element is in operative position, is arranged parallel to a vertically disposed 25 roller 36, the latter being carried by supports 37, 38, the latter being shiftable upward through a plate 39 to enable said roller 36 to be removed and positioned at an adjacent track when occasion so requires. 30 The rollers 35 and 36 are employed for smoothing out the flexible body 26 as the same moves against the backing plate 31. The backing plate is offset so as to extend between the top and bottom rails of the carrier whereby the flexible body 26 will lie 35 against said backing plate 31 so the necessary support will be had during the pasting of the poster or map upon the body.

The track rails shown in Fig. 1 are indi-

- 40 cated by the reference characters 40, 41, 42 and 43. The backing elements by the reference characters 44 and 45. But one track rail is employed at a time and the backing element is shifted to operative position with 45 respect to the carrier which is being moved upon the track way. The inclined portions 9 of a track rail are employed for widening the carrier to draw the flexible body 26 taut. The inclined portions 9 of a track rail are 50 arranged in the position to draw the flexible body taut immediately in advance of said flexible body passing in position over the backing plate 31.

When using the device the flexible body 55 26 is detachably connected to the carrier by the coupling or adjusting members 25 and after the flexible body is drawn taut, due to the inclined portion 9 of the track rail 2, it is then positioned against the backing plate 60 31 of the backing element, the poster or map is then pasted to the flexible body 26, the carrier is then shifted and the mounting is then allowed to dry. By making the carrier of a necessary length the flexible body can 65 be substantially the same length and the

posters or maps can be pasted upon the flexible body 26, under such condition saving a considerable amount of cloth particularly in view of the fact that in the mode now in general use the poster is cut according to 70 the size of the picture and during the cutting considerable waste is had. When more than one track rail is employed the track rails are positioned the necessary distance apart so as not to interfere with the operation when one track way has been used and the second one is to be employed. The length of a carrier is such as not to interfere with the operation of the backing elements after one track way has been employed and a new one is to be used. 75

What I claim is:—

1. A mounting apparatus comprising a track way, a carrier traveling thereon and supporting a flexible body, means whereby 85 said body can be contracted and extended during the shifting of the carrier, and a backing element shiftable transversely with respect to said track way and adapted to support the flexible body mounted upon 90 the carrier during the pasting of a poster or map upon the body.
2. A mounting apparatus comprising a track way, a carrier traveling thereon and supporting a flexible body, means whereby 95 said body can be contracted and extended during the shifting of the carrier, and a backing element shiftable transversely with respect to said track way and adapted to support the flexible body mounted upon the 100 carrier during the pasting of a poster or map upon the body, said backing element provided with a track forming a continuation of a lower track of said track way.

3. A mounting apparatus comprising a 105 track way, a carrier traveling thereon and supporting a flexible body, means whereby said body can be contracted and extended during the shifting of the carrier, and a backing element shiftable transversely with 110 respect to said track way and adapted to support the flexible body mounted upon the carrier during the pasting of a poster or map upon the body, and means for smoothing out the flexible body mounted upon the 115 carrier prior to the positioning of the flexible body with respect to the backing element.

4. A mounting apparatus comprising a track way, a carrier traveling thereon and supporting a flexible body, means whereby 120 said body can be contracted and extended during the shifting of the carrier, and a backing element shiftable transversely with respect to said track way and adapted to support the flexible body mounted upon the 125 carrier during the pasting of a poster or map upon the body, said backing element provided with a track forming a continuation of a lower track of said track way, and means for smoothing out the flexible 130

flexible body contracting after having pasted thereon a poster or map, and said backing element provided with means to form a continuation of one of the tracks of said track 5 ways.

14. A mounting apparatus comprising a track way, a portable carrier mounted upon said track way and adapted to support a flexible body constituting the backing of a 10 mounting, and a portable backing element moving in the plane at right angles to the plane of the movement of the carrier and adapted to support the flexible body mounted upon the carrier during the pasting of a 15 poster or map upon said flexible body, and means for smoothing out the flexible body prior to the positioning thereof with respect to the backing element, and said backing element provided with means to constitute a 20 continuation of one of the tracks of said track way.

15. A mounting apparatus comprising a track way, a portable carrier mounted upon said track way and adapted to support a flexible body constituting the backing of a mounting, and a portable backing element moving in the plane at right angles to the plane of the movement of the carrier and adapted to support the flexible body mounted upon the carrier during the pasting of a poster or map upon said flexible body, and means for extending the carrier to draw said flexible body taut prior to the pasting thereon of a poster or map, and means for smoothing out the flexible body prior to the positioning thereof with respect to the backing element, and said backing element pro-

Copies of this patent may be obtained for five cents each, by addressing the "Commissioner of Patents, Washington, D. C."

vided with means to constitute a continuation of one of the tracks of said track way.

16. A mounting apparatus comprising a track way, a portable carrier mounted upon said track way and adapted to support a flexible body constituting the backing of a mounting, and a portable backing element moving in the plane at right angles to the plane of the movement of the carrier and adapted to support the flexible body mounted upon the carrier during the pasting of a poster or map upon said flexible body, and means for extending the carrier to draw said body taut prior to the pasting thereon of a poster or map, and means to permit of said flexible body contracting after having pasted thereon a poster or map, and means for smoothing out the flexible body prior to the positioning thereof with respect to the backing element, and said backing element provided with means to constitute a continuation of one of the tracks of said track way.

17. A mounting apparatus comprising a track way, a carrier traveling thereon and supporting a flexible body, means whereby said body can be contracted and expanded during the shifting of the carrier and a backing element co-operating with the carrier and adapted to support the flexible body during the pasting of a poster or map thereon. 60 65

In testimony whereof I affix my signature
in presence of two witnesses.

ELMER LEE HARMON.
